UNITED STATES PATENT OFFICE.

AMOS F. GERALD, OF FAIRFIELD, MAINE, ASSIGNOR TO THE GERALD SEWING MACHINE CABINET COMPANY, OF NEW YORK, N. Y.

MEANS FOR SUSTAINING DOWEL-PINS OR HINGE-PINS.

SPECIFICATION forming part of Letters Patent No. 293,646, dated February 19, 1884.

Application filed July 11, 1883. (No model.)

To all whom it may concern:

Be it known that I, AMOS F. GERALD, of 5
Fairfield, in the county of Somerset and State
of Maine, have invented a certain new and
useful Improvement in Means for Sustaining
Dowel-Pins or Hinge-Pins, of which the fol-
lowing is a specification.

Dowel and hinge pins made of metal or wood
and inserted into pieces of wood are apt, when
10 subjected to great strain, to break away or
split the pieces of wood into which they are
inserted.

The object of my present invention is to ob-
viate this occurrence.

15 To this end the improvement consists in the
combination, with a dowel or hinge pin and a
piece of wood into which it is inserted or to
be inserted, of a strip of metal inserted into
the piece of wood so as to extend around the
20 pin and into a portion of the piece of wood at
some distance from the pin.

In the accompanying drawings, Figure 1 is
an end view of a piece of wood, having in-
25 inserted into it a dowel-pin or hinge-pin, and
also a strip of metal, in accordance with my
invention; and Fig. 2 is a longitudinal section
of the piece of wood, and a side view of the
pin and strip of metal.

Similar letters of reference designate corre-
30 sponding parts in both figures.

A designates a piece of wood, which may
form part of a door.

B designates a pin, which forms one of a
35 pair of hinge-pins, whereby the article of
which the piece of wood A forms part is
hinged in place. This pin is round, and is
preferably made of metal. It is inserted in
one end of the piece of wood A, close to one
40 corner thereof. So thin is the wood between
this pin and the adjacent corner of the piece
of wood A that any severe strain upon the pin
would break the wood away and loosen the
pin.

C designates a strip of metal, preferably
steel, which is bent to surround the rod, and
is driven into the end of the piece of wood A.
It extends close to the pin at the point where
the wood is apt to be broken away by a strain
upon the pin, but it extends considerably be-
yond the pin in the opposite direction. As
shown, this strip of metal is bent lengthwise
into the shape of a heart, and is then driven
into the piece of wood. The obtuse point of
the heart surrounds the pin, and the ends of
the strip are bent into proximity at the place
where the opposite indentation of the heart
occurs. I have found that this shape is very
advantageous. The strip gets a good hold on
portions of the piece of wood which are dis-
tant from the pin, and hence it will brace and
hold the pin firmly.

The strip of metal need not be of any great
depth, as it will prove efficacious, even if it
sustain but the upper portion of the pin.

Dowel-pins may be braced in the same way
as hinge-pins.

What I claim as my invention, and desire to
secure by Letters Patent, is—

1. The combination, with a dowel or hinge
pin and a piece of wood into which it is in-
35 serted or to be inserted, of a strip of metal in-
serted into the piece of wood so as to extend
around the pin and into a portion of wood at
some distance from the pin, substantially as
specified.

2. The combination, with a dowel or hinge
pin and a piece of wood into which it is in-
40 serted or to be inserted, of a strip of metal
bent into the shape of a heart and inserted into
the piece of wood so that the obtuse point will
extend close to the pin, substantially as speci-
fied.

AMOS F. GERALD.
